(57) **CLAIM**

The ornamental design for a cabinet, as shown and described.

DESCRIPTION

FIG. 1 is a front, top, and right perspective view of a first embodiment of a cabinet, showing my new design; FIG. 2 is a rear, bottom, and left perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of detail "9" in FIG. 1; FIG. 10 is a front, top, and right perspective view of a second embodiment of the cabinet; FIG. 11 is a rear, bottom, and left perspective view thereof; FIG. 12 is a front view thereof; FIG. 13 is a rear view thereof; FIG. 14 is a left side view thereof; FIG. 15 is a right side view thereof; FIG. 16 is a top view thereof; FIG. 17 is a bottom view thereof; FIG. 18 is an enlarged view of detail "18" in FIG. 10; FIG. 19 is a front, top, and right perspective view of a third embodiment of the cabinet; FIG. 20 is a rear, bottom, and left perspective view thereof; FIG. 21 is a front view thereof; FIG. 22 is a rear view thereof; FIG. 23 is a left side view thereof; FIG. 24 is a right side view thereof; FIG. 25 is a top view thereof; FIG. 26 is a bottom view thereof; FIG. 27 is an enlarged view of detail "27" in FIG. 19; FIG. 28 is a front and top, and right perspective view of a fourth embodiment of the cabinet; FIG. 29 is a rear, bottom, and left perspective view thereof; FIG. 30 is a front view thereof; FIG. 31 is a rear view thereof; FIG. 32 is a left side view thereof; FIG. 33 is a right side view thereof; FIG. 34 is a top view thereof; FIG. 35 is a bottom view thereof; FIG. 36 is an enlarged view of detail "36" in FIG. 28; FIG. 37 is a front, top, and right perspective view of a fifth embodiment of the cabinet;

(Continued)

FIG. 38 is a rear, bottom, and left perspective view thereof;
FIG. 39 is a front view thereof;
FIG. 40 is a rear view thereof;
FIG. 41 is a left side view thereof;
FIG. 42 is a right side view thereof;
FIG. 43 is a top view thereof;
FIG. 44 is a bottom view thereof;
FIG. 45 is an enlarged view of detail "45" in FIG. 37;
FIG. 46 is a front, top, and right perspective view of a sixth embodiment of the cabinet;
FIG. 47 is a rear, bottom, and left perspective view thereof;
FIG. 48 is a front view thereof;
FIG. 49 is a rear view thereof;
FIG. 50 is a left side view thereof;
FIG. 51 is a right side view thereof;
FIG. 52 is a top view thereof;
FIG. 53 is a bottom view thereof; and,
FIG. 54 is an enlarged view of detail "54" in FIG. 46.
The dashed lines in the figures illustrate portions of the cabinet that form no part of the claimed design.
